kilogram of host body weight per minute (mp.k./min.). Changes in contractile force are generally expressed as a percentage of the control value using epinephrine or quinidine as a standard compound. The value of this method lies in the ability to simultaneously measure changes in blood pressure and changes in the force of contraction of the heart. An active compound increases the myocardial contractile force.

When tested in the foregoing procedure the compounds of the present invention increased the myocardial contractile force from about 40 to over 100 percent.

The final compounds of the invention may be in the natural or *d*-form, but preferably are in the racemic or *dl*-form. Most advantageous results may be obtained with the *l*-form. The steroid moiety exerts sex hormonal activity in addition to the cardiotonic or digitalis-like effect found for these compounds when the steroid moiety is in the natural or *d*-form. The *l*-form compounds do not have the sex hormonal side effects. The *dl*-form has reduced side effects. Compounds designated as the *d*-forms are the enantiomers corresponding in configuration at C-13 to that of the natural hormone estrone following a convention approved by Fieser and Fieser in "Steroids," p. 336 (1959). The corresponding enantiomorphs are then designated the *l*-forms and the racemates the *dl*-forms.

To obtain the *l*-form steroids the starting materials are resolved during synthesis. If a resolution stage is not used, the synthetic compounds will be present in the *dl*-form. Resolution of the racemic compounds prior to forming the contemplated bis(amidinohydrzones) can be done by known procedures. One such resolution method is disclosed by Buzby et al. in Jour. Med. Chem., 10, 199 (1967).

When the compounds of this invention are employed as described above, they may be administered alone or in combination with pharmacologically acceptable carriers, the proportion of which is determined by the solubility and chemical nature of the compound, chosen route of administration and standard pharmacological practice. For example, they may be administered orally in the form of tablets or capsules containing such excipients as starch, milk, sugar, certain types of clay and so forth. They may be administered sublingually in the form of troches or lozenges in which the active ingredient is mixed with sugar and corn syrups, and then dehydrated sufficiently to make it suitable for pressing into a solid form. They may be administered orally in the form of solutions which may contain coloring and flavoring agents or they may be injected parenterally, that is intramuscularly, intravenously or subcutaneously. For parenteral administration they may be used in the form of sterile solution containing other solutes, for example, enough saline or glucose to make the solution isotonic.

The dosage of the present therapeutic agents will vary with the form of administration and the particular compound chosen. Furthermore, it will vary with the particular subject under treatment. Generally, treatment is initiated with small dosages substantially less than the optimum dose of the compound. Thereafter, the dosage is increased by small increments until the optimum effect under the circumstances is reached. It will generally be found that when the composition is administered orally, larger quantities of the active agent will be required to produce the same effect as a smaller quantity given parenterally. In general, the compounds of this invention are most desirably administered at a concentration level that will generally afford effective results without causing any harmful or deleterious side effects.

In order more clearly to disclose the nature of the present invention, specific examples of the practice of the invention are hereinafter given. It should be understood, however, that this is done solely by way of example and is intended neither to delineate the scope of the invention nor limit the ambit of the appended claims.

In the examples all of the temperatures are stated in degrees centigrade, and the following abbreviations are used: "gm." for grams, "ml." for milliliters, "N" for normal, "mg." for milligrams, and "dec." to denote decomposition at the "melting point."

EXAMPLE 1

13-ethylgon-4-ene-3,17-dione, bis(amidinohydrazone) dihydrochloride, hemihydrate

10 To a solution of 2.0 gm. of 13-ethylgon-4-ene-3,17-dione in 20 ml. of methanol is added a solution of 3.0 gm. of aminoguanidine bicarbonate in 25 ml. of methanol which had been acidified with 5.5 N hydrochloric acid in isopropanol. The reaction mixture is evaporated to about half of its volume on a steam bath. The mixture is cooled and ether is added to incipient turbidity. The resulting precipitate is recrystallized from methanol-ether-acetone to yield 13-ethylgon-4-ene-3,17-dione, bis(amidinohydrazone) dihydrochloride, hemihydrate which decomposed at about 333°.

Analysis.—Calcd. for $C_{21}H_{34}N_8 \cdot 2HCl \cdot \frac{1}{2}H_2O$ (percent): C, 52.49; H, 7.76; Cl, 14.76; H_2O , 1.88. Found (percent): C, 52.75; H, 7.65; Cl, 14.80; H_2O , 1.62.

In the foregoing pharmacological procedure the product was found to increase the myocardial contractile force 82 percent.

Similarly, following the procedure set forth in Example 1, but substituting an equivalent amount of sulfuric acid in isopropanol for the hydrochloric acid, yields the sulfate salt of 13-ethylgon-4-ene-3,17-dione, bis(amidinohydrazone).

EXAMPLE 2

13-propylgon-4-ene-3,17-dione, bis(amidinohydrazone) diacetate

35 Following the procedure described in Example 1, but substituting 13-propylgon-4-ene-3,17-dione for 13-ethylgon-4-ene-3,17-dione and utilizing acetic acid in lieu of hydrochloric acid there is obtained 13-propylgon-4-ene-3,17-dione, bis(amidinohydrazone) diacetate.

EXAMPLE 3

13-ethylgona-4,9-diene-3,17-dione, bis(amidinohydrazone) dihydrochloride

45 Following the procedure of Example 1, but substituting 13-ethylgona-4,9-diene-3,17-dione for 13-ethylgon-4-ene-3,17-dione there is obtained 13-ethylgona-4,9-diene-3,17-dione, bis(amidinohydrazone) dihydrochloride.

In the foregoing pharmacological procedure the product was found to increase the myocardial contractile force 81 percent.

EXAMPLE 4

13-ethylgona-4,6-diene-3,17-dione, bis(amidinohydrazone) dihydrochloride

55 Following the procedure of Example 1, but substituting 13-ethylgona-4,6-diene-3,17-dione for 13-ethylgon-4-ene-3,17-dione there is obtained 13-ethylgona-4,6-diene-3,17-dione, bis(amidinohydrazone) dihydrochloride.

EXAMPLE 5

13-propylgona-4,9-diene-3,17-dione, bis(amidinohydrazone) dihydrochloride

60 Following the procedure of Example 1, but substituting 13-propylgona-4,9-diene-3,17-dione for 13-ethylgon-4-ene-3,17-dione there is obtained 13-propylgona-4,9-diene-3,17-dione, bis(amidinohydrazone) dihydrochloride.

EXAMPLE 6

13-ethyl-5 α -gonane-3,17-dione, bis(amidinohydrazone) dihydrochloride, hydrate

70 Following the procedure of Example 1, but substituting 13-ethyl-5 α -gonane-3,17-dione for 13-ethylgon-4-ene-3,17-dione, there is obtained 13-ethyl-5 α -gonane-3,17-dione,

5

bis(amidinohydrazone) dihydrochloride, hydrate having a melting point of 336° (dec.);

$\lambda_{\text{max.}}^{\text{KBr}}$ 3.16, 6.00 μ .

Analysis.—Calcd. for $\text{C}_{21}\text{H}_{38}\text{N}_8 \cdot 2\text{HCl} \cdot 1/4\text{H}_2\text{O}$ (percent): C, 52.77; H, 8.12; N, 23.44; Cl, 14.84. Found (percent): C, 52.59; H, 7.71; N, 23.20; Cl, 14.90.

In the foregoing pharmacological procedure the product was found to increase the myocardial contractile force 85 percent.

EXAMPLE 7

13-ethylgona-4,9-diene-3,17-dione, bis(amidinohydrazone) dihydrochloride, dihydrate

To a solution of 800 mg. of 13-ethylgona-4,9-diene-3,17-dione, 3-amidinohydrazone, hydrochloride in 30 ml. of methanol is added a solution of 800 mg. of aminoguanidine bicarbonate in 30 ml. of methanol, which had been acidified to pH 2 with isopropanolic hydrochloric acid (8.6 N). The resulting solution is left at room temperature for 4 days. Ether is added and the resulting precipitate is crystallized from methanol-acetone to yield 600 mg. of 13-ethylgona-4,9-diene-3,17-dione, bis(amidinohydrazone) dihydrochloride, dihydrate having a melting point of 240–250° (dec.).

Analysis.—Calcd. for

$\text{C}_{21}\text{H}_{32}\text{N}_8 \cdot 2\text{HCl} \cdot 2\text{H}_2\text{O}$

N, 22.26%. Found: N, 22.15%.

EXAMPLE 8

6-methyl-13-ethylgon-4-ene-3,17-dione, bis(amidinohydrazone) dihydrochloride

Following the procedure of Example 1, but substituting 6-methyl-13-ethylgon-4-ene-3,17-dione for 13-ethylgon-4-ene-3,17-dione there is obtained 6-methyl-13-ethylgon-4-ene-3,17-dione, bis(amidinohydrazone) dihydrochloride.

EXAMPLE 9

13-ethyl-18,19-dinorpregn-4-ene-3,20-dione, bis(amidinohydrazone) dihydrochloride

To a solution of 0.10 gm. of 13-ethyl-18,19-dinorpregn-4-ene-3,20-dione in 5.0 ml. of hot methanol is added a solution of 0.15 gm. of aminoguanidine bicarbonate in 5.0 ml. of methanol which is acidified with 5.5 N of hydrochloric acid in isopropanol. The solution is heated on a steam bath for 15 minutes and cooled at 0° to yield 115 mg. of crystalline 13-ethyl-18,19-dinorpregn-4-ene-3,20-dione, bis(amidinohydrazone) dihydrochloride having a melting point of 338–340° (dec.);

$\lambda_{\text{max.}}^{\text{KBr}}$ 6.01 and 6.15 μ ; $\lambda_{\text{max.}}^{\text{ECD}}$ 236 m μ

(ϵ =23,900) and 276 m μ (ϵ =32,900).

Analysis.—Calcd. for $\text{C}_{23}\text{H}_{38}\text{N}_8 \cdot 2\text{HCl}$ (percent): C, 55.30; H, 8.07; N, 22.44; Cl, 14.20. Found (percent): C, 54.92; H, 8.36; N, 22.39; Cl, 14.20.

EXAMPLE 10

13-propyl-18,19-dinorpregn-4-ene-3,20-dione, bis(amidinohydrazone) dihydrochloride

Following the procedure of Example 9, but substituting 13-propyl-18,19-dinorpregn-4-ene-3,20-dione for 13-ethyl-18,19-dinorpregn-4-ene-3,20-dione there is obtained 13-propyl-18,19-dinorpregn-4-ene-3,20-dione, bis(amidinohydrazone) dihydrochloride.

EXAMPLE 11

13-ethyl-16-methoxy-18,19-dinorpregn-4-ene-3,20-dione, bis(amidinohydrazone) dihydrochloride

Following the procedure of Example 9, but substituting 13-ethyl-16-methoxy-18,19-dinorpregn-4-ene-3,20-dione for 13-ethyl-18,19-dinorpregn-4-ene-3,20-dione there is obtained 13-ethyl-16-methoxy-18,19-dinorpregn-4-ene-3,20-dione, bis(amidinohydrazone) dihydrochloride.

6

EXAMPLE 12

6-methyl-13-ethyl-18,19-dinorpregn-4-ene-3,20-dione, bis(amidinohydrazone) dihydrochloride

5 Following the procedure of Example 9, but substituting 6-methyl-13-ethyl-18,19-dinorpregn-4-ene-3,20-dione for 13-ethyl-18,19-dinorpregn-4-ene-3,20-dione there is obtained 6-methyl-13-ethyl-18,19-dinorpregn-4-ene-3,20-dione, bis(amidinohydrazone) dihydrochloride.

10
15 Following the procedure of Example 9, but substituting 13-ethyl-18,19-dinorpregn-4,6-diene-3,20-dione for 13-ethyl-18,19-dinorpregn-4-ene-3,20-dione there is obtained 13-ethyl-18,19-dinorpregn-4,6-diene-3,20-dione, bis(amidinohydrazone) dihydrochloride.

EXAMPLE 13

13-ethyl-18,19-dinorpregn-4,6-diene-3,20-dione, bis(amidinohydrazone) dihydrochloride

20
25 Following the procedure of Example 9, but substituting 13-ethyl-18,19-dinorpregn-4,9-diene-3,20-dione for 13-ethyl-18,19-dinorpregn-4-ene-3,20-dione there is obtained 13-ethyl-18,19-dinorpregn-4,9-diene-3,20-dione, bis(amidinohydrazone) dihydrochloride.

EXAMPLE 14

13-ethyl-18,19-dinorpregn-4,9-diene-3,20-dione, bis(amidinohydrazone) dihydrochloride

30
35 Following the procedure of Example 9, but substituting 13-ethyl-18,19-dinorpregn-4,9-diene-3,20-dione for 13-ethyl-18,19-dinorpregn-4-ene-3,20-dione there is obtained 13-ethyl-18,19-dinorpregn-4,9-diene-3,20-dione, bis(amidinohydrazone) dihydrochloride.

EXAMPLE 15

13-ethyl-18,19-dinor-5 α -pregnane-3,20-dione, bis(amidinohydrazone) dihydrochloride

40
45 Following the procedure of Example 9, but substituting 13-ethyl-18,19-dinor-5 α -pregnane-3,20-dione for 13-ethyl-18,19-dinorpregn-4-ene-3,20-dione there is obtained 13-ethyl-18,19-dinor-5 α -pregnane-3,20-dione, bis(amidinohydrazone) dihydrochloride.

EXAMPLE 16

13-ethylgona-4,9-diene-3,17-dione, bis(amidinohydrazone), dinitrate

50
55 To a hot solution of 2.2 gm. of aminoguanidine, nitrate and 60 ml. of methanol is added 1.3 gm. of 13-ethylgona-4,9-diene-3,17-dione. The pH is adjusted to 2 and the reaction mixture is stirred at 37° for 3 days. A crystalline product forms and is filtered to yield 1.6 gm. of 13-ethylgona-4,9-diene-3,17-dione, bis(amidinohydrazone), dinitrate having a melting point of 252–257° (dec.).

Analysis.—Calcd. for $\text{C}_{21}\text{H}_{32}\text{N}_8 \cdot 2\text{HNO}_3$ (percent): C, 48.26; H, 6.56; N, 26.80. Found (percent): C, 48.09; H, 6.52; N, 25.81.

EXAMPLE 17

13-propylgona-4,9-diene-3,17-dione, bis(amidinohydrazone), dinitrate

60 A hot solution of 740 mg. of aminoguanidine, nitrate and 18 ml. of methanol is treated with 400 mg. of 13-propylgona-4,9-diene-3,17-dione. The reaction is brought to pH 2 with 7% nitric acid and stirred for 4 days at approximately 37° while reducing the volume to 9 ml.

65 by passing nitrogen over the mixture. The resulting mixture is filtered and the precipitate is washed with methanol and acetone to yield 400 mg. of 13-propylgona-4,9-diene-3,17-dione, bis(amidinohydrazone), dinitrate having a melting point of 238–240° (dec.);

70
75 $\lambda_{\text{max.}}^{\text{KBr}}$ 3.20, 5.96, 6.10, 6.25 μ

Analysis.—Calcd. for $\text{C}_{22}\text{H}_{34}\text{N}_8 \cdot 2\text{HNO}_3$ (percent): C, 49.24; H, 6.76; N, 26.11. Found (percent): C, 49.03; H, 6.35; N, 26.10.

7
EXAMPLE 18

13-ethylgona-4,6-diene-3,17-dione, bis(amidino-hydrazone), dinitrate

A mixture of 1.2 gm. of 13-ethylgona-4,6-diene-3,17-dione, 3-amidinohydrazone, nitrate, 70 ml. of methanol, and 1.2 g. of aminoguanidine, nitrate is adjusted to pH 2.5 with 7% nitric acid and refluxed for 2.5 hours. The reaction mixture is then evaporated to 35 ml. and the resulting precipitate filtered. The precipitate is recrystallized with aqueous ethanol, the material filtered off and the clear mother liquor is kept at room temperature for 2 days to yield 13-ethylgona-4,6-diene-3,17-dione, bis(amidinohydrazone), dinitrate having a melting point of 260° (dec.).

Analysis.—Calcd. for $C_{22}H_{32}N_8 \cdot 2HNO_3$ (percent): C, 48.26; H, 6.50. Found (percent): C, 48.81; H, 6.60.

EXAMPLE 19

13-ethylgona-4,6-diene-3,17-dione, 3-amidino-hydrazone, nitrate

To a warm solution of 2.5 gm. of aminoguanidine nitrate in 70 ml. of methanol is added 1.5 g. of 13-ethylgona-4,6-diene-3,17-dione. The resulting solution is brought to pH 2 with 7% nitric acid and stirred for 3 days to yield 1.2 g. of 13-ethylgona-4,6-diene-3,17-dione, 3-amidinohydrazone, nitrate having a melting point of 247–250°.

Analysis.—Calcd. for $C_{20}H_{28}ON_4 \cdot HNO_3$: N, 17.36%. Found: N, 17.03%.

EXAMPLE 20

13-ethylgona-4,9-diene-3,17-dione, 3-amidinohydrazone, hydrochloride

To a solution of 2.0 gm. of aminoguanidine bicarbonate in 40 ml. of methanol acidified to pH 1 with isopropanolic hydrochloric acid (8.6 N) is added 2.0 gm. of 13-ethylgona-4,9-diene-3,17-dione in 40 ml. of methanol. The reaction mixture is stirred while passing nitrogen over it to reduce the volume to 40 ml. over a period of 18 hours. The resulting precipitate is filtered to yield 1.2 gm. of 13-ethylgona-4,9-diene-3,17-dione, 3-amidinohydrazone, hydrochloride having a melting point of 280° (dec.).

Analysis.—Calcd. for $C_{20}H_{28}N_4O \cdot HCl$ (percent): C, 63.73; H, 7.75; N, 14.85; Cl, 9.41. Found (percent): C, 63.77; H, 7.35; N, 14.50; Cl, 9.80.

It is understood that the acid addition salts of Examples 1 through 20 can be converted to their free bases by any conventional method.

It is further understood that the D-homo steroids are included within the scope of the invention.

It is also understood that either the *dl*-steroids or specific *d* or *l*-isomers may be employed as starting materials with like chemical results.

The terms and expressions which have been employed are used as terms of description and not of limitation, and there is no intention in the use of such terms and expressions of excluding any equivalents of the features shown and described or portions thereof, but it is recognized that various modifications are possible within the scope of the invention claimed.

What is claimed is:

1. A compound of the formula

8

and the pharmaceutically acceptable acid-addition salts thereof, wherein the 4,5-position is unsaturated, and one of the 6,7- and 9,10-positions is also unsaturated; R is an alkyl group of 2 to 8 carbon atoms;

R¹ is selected from the group consisting of hydrogen, an alkyl of less than 5 carbon atoms, hydroxy and lower alkoxy;

R² is selected from the group consisting of hydrogen and methyl; and

10 Z is selected from the group consisting of

wherein R³ is selected from the group consisting of hydrogen and hydroxy, with the proviso that R¹ is hydroxy and lower alkoxy only when Z is

2. A compound according to claim 1 having the structural formula

and the pharmaceutically acceptable acid-addition salts thereof, wherein W is an unsaturated linkage between C-9 and C-10, and R is an alkyl group of 2 to 8 carbon atoms.

3. A compound according to claim 1 having the structural formula

70 and the pharmaceutically acceptable acid-addition salts thereof, wherein W' is an unsaturated linkage between C-4 and C-5; W'' is an unsaturated linkage between C-6 and C-7; and R is an alkyl group of 2 to 8 carbon atoms.

4. A compound according to claim 1 which comprises the pharmaceutically acceptable acid-addition salt of 13-75 ethylgona-4,9-diene-3,17-dione, bis(amidino hydrazone).

5. A compound according to claim 1 which comprises the pharmaceutically acceptable acid-addition salt of 13-ethylgona-4,6-diene-3,17-dione, bis(amidinohydrazone).

6. A compound according to claim 1 which comprises the pharmaceutically acceptable acid-addition salt of 13-propylgona-4,9-diene-3,17-dione, bis(amidinohydrazone).

7. A compound according to claim 1 which comprises the pharmaceutically acceptable acid-addition salt of 13-ethylgona-4,6-diene-3,17-dione, 3-amidinohydrazone.

8. A compound according to claim 1 which comprises 10 the pharmaceutically acceptable acid-addition salt of 13-ethylgona-4,9-diene-3,17-dione, 3-amidinohydrazone.
